PIANO FALL-BOARD

Edward L. Schroth, Cheviot, Ohio, assignor to
 The Baldwin Company, Cincinnati, Ohio, a corporation of Ohio

Application December 3, 1947, Serial No. 789,447

10 Claims. (Cl. 84—179)

1

This invention relates to the construction of pianos and in particular to a piano fall-board adapted for use in small upright pianos, in which the action is at least partially below the keyboard level.

A primary object of the invention is to provide a one-piece, readily operable fall-board which will occupy a minimum of vertical space so that the music desk can be located as near as possible to the plane of the keyboard.

Another object of the invention is to provide a fall-board having the above advantages and which will at the same time, clear the key action mechanism of the piano.

An additional object of the invention is to provide in connection with my fall-board an equalizer mechanism in which the inherent back-lash is held to a minimum, and which assures smooth and easy action.

Still another object is to provide a fall-board which can be operated easily and quietly in the covering or uncovering of the keyboard.

A further object is to provide an economical construction which is simple to manufacture, requires no separate hinges, and is quickly and easily installed in the piano.

It is an object of my invention to provide a simple mechanism which will not only guide the fall-board in its rearward motion and prevent cocking during motion in both directions but which will also provide a virtual hinge for the fall-board in its fully withdrawn position to permit a downward tilting of the fall-board to cover the keys.

These and other objects of the invention which will be set forth hereinafter or will be apparent to one skilled in the art from the following teachings, I attain by that arrangement and in that mode of operation of which I shall now describe an exemplary embodiment. Reference is made to accompanying drawings wherein:

Figure 1 is a sectional, fragmentary side view of a piano, taken just inside both the treble or right-hand end and the right-hand keyblock, including a fall-board constructed in accordance with the present invention, showing the fall-board in the closed position, in which the operable portions of the keys are covered;

Figure 2 is a similar view, but with the fall-board in its open position, exposing the operable portions of the keys; and

Figure 3 is a partial sectional view, taken along

the line A—A in Figure 2, which shows the detail of a pivoted guide member.

The fall-board assembly (see Figure 1) comprises the inclined portion 1 joined at an obtuse angle to the vertical front portion 2, arranged so as to enclose the manually operable part of the keyboard 3. It includes the U-shaped equalizer rod 4, the cross-portion of which is pivotally fastened by means of bushed bearing clips 12 to the rear edge of the fall-board inclined portion 1. The arms of the equalizer 4 respectively engage in slidable relationship the pivoted guide-members 5, one on each side of the piano. I prefer to curve the upper surface of the inclined portion 2 to improve the design appearance.

In conjunction with the fall-board assembly are shown the piano top 6, the music desk 7, the fall-board knobs 8, the keyslip 9, and the keystrip 10. Keyblocks 11 are located at each side 20 of the key assemblies.

The piano shelf 15 extends between the end members 18 of the piano case, and its lower surface may be lined in full or in part with a felt liner 16 to protect the finish on the upper surface 25 of the inclined portion 1 of the fall-board.

The guide members 5 are pivoted to the end members 18 of the piano case by means of screws 17, preferably somewhat above and to the rear of the rear edge of the key bed 20, but in any event below the rear edge of the fall-board in its rearward position.

Slides 14 are provided for the rearward translation of the fall-board, and may be fastened as by screws directly to the end members 18.

35 The upper surface of the slides 14 may be coated with a graphite layer to reduce the sliding friction with the under surface of the inclined portion 1 of the fall-board.

The arms of the equalizer rod have a sliding fit in bores in the members 5. The arms must be long enough to engage the guide members 5 in all positions of the fall-board. Stop blocks 13 are fastened, aslant, to the end members 18 of the piano case and in such position as to support the arms of the equalizer rod when the fall-board is fully withdrawn, so that the cross-portion of the equalizer rod can in that position act as a virtual hinge or pivot for the fall-board to permit it to tilt downwardly and cover the keys as in Figure 1.

The fall-board may be shifted from its closed position as shown in Figure 1 to the open position

shown in Figure 2 by lifting the front of the fall-board by means of the knobs 8 until the inclined portion 1 is horizontal, and then pushing the fall-board toward the rear. The upper surface of the keyblocks 11 serve generally to guide the movement and to keep the vertical portion 2 clear of the keyboard 3. The equalizer rod 4, the cross-portion of which parallels the back edge of the inclined portion 1 of the fall-board, being attached to it by means of the bushed bearing clips 12, causes both ends of the fall-board to recede equally, thus preventing misalignment and possible jamming during the movement. The front edge of the slides 14 act as stops to the rearward movement of the fall-board. The stop-blocks 13 limit the travel of the fall-board by virtue of their position in the path of the arms of the equalizer rod 4.

Figure 3 illustrates the manner in which the arms of the equalizer 4 engage the pivoted guide-member 5. The screw 17, embedded in the end member 18 of the piano case, acts as a pivot about which the guide member 5 can rotate. A washer 19 surrounding the screw 17 and interposed between the guide member 5 and the support 18 facilitates smooth rotation of the guide member.

It can readily be seen that, if a close mechanical fit is maintained between the bearing clips 12 and the cross-portion of the equalizer rod 4, between the guide members 5 and the arms of the equalizer rod 4, and between the guide-members 5 and the screws 17, practically no back-lash will be present, and both ends of the fall-board must move equally, without cocking.

Modifications can be made in my invention without departing from the spirit of it. Having thus described my invention in an exemplary embodiment, what I claim as new and desire to secure by Letters Patent is:

1. In combination in a musical instrument, a case, two ends for said case, a keyboard disposed horizontally between said ends, a fall-board having a covering and an uncovering position with respect to said keyboard, slides for said fall-board, an equalizing mechanism comprising a U-shaped member having a cross-portion with two arms connected thereto, and two guides pivoted on said ends, said cross-portion being pivotally connected to said fall-board and said arms having a slidable relationship with respect to said pivoted guides.

2. The combination as set forth in claim 1, including stop blocks located on said ends, said arms of said equalizer being disposed against said stop-blocks in said covering position.

3. The combination as set forth in claim 1, in which each of said pivoted guides comprises a block having a transverse hole acting as a bearing for the pivot of said guide and a longitudinal hole acting as a sliding bearing for one of said arms.

4. The combination as set forth in claim 1, including a strip in front of said keyboard and a front portion on said fall-board, said front portion of said fall-board having a substantially co-planar relationship with said strip in said first position.

5. In combination in a musical instrument, a horizontally disposed keyboard, slides located behind and above the playable portion of said keyboard, a fall-board comprising essentially a rigid structure composed of a rear portion and a front portion, said portions being joined at an angle to form said rigid structure, a shelf located above said slides at a distance greater than the maximum thickness of said rear portion of said fall-

board, pivoted guide members located behind and below said slides, and a U-shaped equalizer member comprising a longitudinal portion and two downwardly extending arms, said longitudinal portion having pivotal connections with the rear edge of said rear portion of said fall-board and said arms having a slidable relationship with said pivoted guide members, said fall-board being manually movable to a closed position, wherein 10 said fall-board covers said keyboard.

6. The combination as set forth in claim 5, including stop-blocks located below said slides, said arms of said equalizer being disposed against said stop-blocks when said fall-board is in the covering position.

7. In a piano having a case with end members, a keyboard, a keyslip in front of said keyboard, a key strip above the rear portion of said keyboard, a shelf spaced above said key strip, a fall-board having a body portion and a front portion in rigid union and movable from a covering position in which said body portion is downwardly tilted and said front portion is substantially co-planar with said keyslip to an uncovering position in which said body portion is substantially horizontal and said front portion substantially closes the space between said shelf and said key strip, and an equalizer rod for said fall-board having a cross-portion pivoted to the rear edge of said fall-board, and depending arms, said arms slidingly pivoted to said end members.

8. In a piano having a case with end members, a keyboard, a keyslip in front of said keyboard, a key strip above the rear portion of said keyboard, a shelf spaced above said key strip, a fall-board having a body portion and a front portion in rigid union and movable from a covering position in which said body portion is downwardly tilted and said front portion is substantially co-planar with said keyslip to an uncovering position in which said body portion is substantially horizontal and said front portion substantially closes the space between said shelf and said key strip, and an equalizer rod for said fall-board having a cross-portion pivoted to the rear edge of said fall-board, and depending arms, said arms slidingly pivoted to said end members, said end members having stop means for said arms in the covering position whereby said equalizer rod forms a pivot for the tilting of said fall-board.

9. In a piano having a case with end members, a keyboard, a keyslip in front of said keyboard, a key strip above the rear portion of said keyboard, a shelf spaced above said key strip, a fall-board having a body portion and a front portion in rigid union and movable from a covering position in which said body portion is downwardly tilted and said front portion is substantially co-planar with said keyslip to an uncovering position in which said body portion is substantially horizontal and said front portion substantially closes the space between said shelf and said key strip, and an equalizer rod for said fall-board having a cross-portion pivoted to the rear edge of said fall-board, and depending arms, said arms slidingly pivoted to said end members, said end members bearing guides engaging end portions of said fall-board body during movement thereof.

10. The combination set forth in claim 6, wherein the rear edge of said rear portion of said fall-board is supported by said equalizer member.

EDWARD L. SCHROTH.
